(57) **CLAIM**

What is claimed is the ornamental design for a handleset, as shown and described.

DESCRIPTION

FIG. 1 is a front perspective view of a handle set of the new design;

FIG. 2 is a front view thereof;

FIG. 3 is a left side view thereof, the right side view being identical;

FIG. 4 is a top view thereof; and,

FIG. 5 is a bottom view thereof.

The broken lines shown represent unclaimed subject matter and form no part of the claimed design.

1 Claim, 4 Drawing Sheets

FIG. 4

FIG. 5
